Ernest William Mackay-Nylas Inventor:

UNITED STATES PATENT OFFICE.

EDWARD WILLIAM MACKENZIE HUGHES, OF CHICAGO, ILLINOIS, ASSIGNOR
TO THE FOX SOLID PRESSED STEEL COMPANY, OF SAME PLACE.

BOLSTER-BEAM FOR CARS.

SPECIFICATION forming part of Letters Patent No. 408,023, dated July 30, 1889.

Application filed January 3, 1889. Serial No. 295,323. (No model.)

To all whom it may concern:

Be it known that I, EDWARD WILLIAM MACKENZIE HUGHES, of Chicago, Cook county, Illinois, have invented a new and useful Improvement

5 in Bolster-Beams for Cars, of which the following is a full, true, and exact description, reference being had to the accompanying drawings.

My invention relates to an improved pressed-steel bolster-beam combining great rigidity, lightness, and durability.

My invention will be readily understood from the accompanying drawings, in which—

Figure 1 represents a plan view of the bolster-beam; Fig. 2, a plan view of the bolster-beam box, and Fig. 3 a section through the bolster-beam and bolster-beam box.

The beam and box are made of pressed steel, and may be made upon the apparatus 20 for which Samson Fox made application on the 18th day of January, 1888, Serial No. 261,166. The end of the bolster-beam box is cut away at C, as shown in Fig. 2, to allow the same to pass through the truck-frames. The 25 part A is deepest in the middle, as shown, and slopes gradually to the ends, the greatest rigidity being required at the center. By making the beam in the form shown in Fig. 1 (being an inverted box) I lessen the weight and

make said bolster-beam very rigid. The said 30 bolster-beam A is provided with openings for the attachment of the wearing-plates and the passage of the king-bolt, as shown.

What I claim as my invention, and desire to secure by Letters Patent, is—

1. A pressed-steel bolster-beam formed of one piece of metal and in the shape of an inverted box having sides and ends integral with the remainder of the box, substantially as described.

2. The combination of the pressed-steel bolster-beam A, formed of one piece of metal, and having sides and ends integral with the beam itself, and the pressed-steel bolster-beam box B, formed of one piece of metal and having 45 sides and ends integral with the beam-box itself, adapted to receive the same, substantially as described.

3. The pressed-steel bolster-beam box B, cut away at the end C for passage through the 50 truck-frame, substantially as described.

In testimony whereof I have signed my name to this specification in the presence of two subscribing witnesses.

EDWARD WILLIAM MACKENZIE HUGHES.
